US00D585387S

(12) **United States Design Patent**
Fukano et al.

(10) **Patent No.:** US D585,387 S
(45) **Date of Patent:** ** Jan. 27, 2009

(54) **INPUT APPARATUS OF ELECTRICAL ACTUATOR**

(75) Inventors: **Yoshihiro Fukano**, Moriya (JP);
Takanori Kochi, Tsukubamirai (JP)

(73) Assignee: **SMC Kabushiki Kaisha**, Tokyo (JP)

(**) Term: **14 Years**

(21) Appl. No.: **29/294,752**

(22) Filed: **Jan. 25, 2008**

(51) LOC (9) Cl. **13-03**

(52) U.S. Cl. **D13/168**

(58) **Field of Classification Search** D13/162,

(57) **CLAIM**

The ornamental design for an input apparatus of electrical actuator, as shown.

DESCRIPTION

FIG. 1 is a top, front and left-side perspective view of an input apparatus of electrical actuator showing our new design;

FIG. 2 is a front view thereof;

FIG. 3 is a rear view thereof;

FIG. 4 is a top plan view thereof;

FIG. 5 is a bottom plan view thereof;

FIG. 6 is a left side view thereof; and,

FIG. 7 is a right side view thereof.

1 Claim, 7 Drawing Sheets

FIG. 1

FIG. 2

FIG. 3

FIG. 4

FIG. 5

FIG. 6

FIG. 7
